UNITED STATES PATENT OFFICE

143,948

DESIGN FOR A SWIM MASK

Jack Browne, Milwaukee, Wis.

Application August 6, 1945, Serial No. 121,256

Term of patent 14 years

(Cl. D83—1)

To all whom it may concern:

Be it known that I, Jack Browne, a citizen of the United States, residing at Milwaukee, in the county of Milwaukee and State of Wisconsin, have invented a new, original, and ornamental Design for a Swim Mask, of which the following is a specification, reference being had to the accompanying drawing, forming part thereof.

The head strap is only fragmentarily shown in Figures 2, 3, 4 and 5, being omitted for convenience of illustration.

The dominant features of the design reside in the portions shown in full lines.

I claim:

The ornamental design for a swim mask, as shown and described.

JACK BROWNE.
